Des. 180,714
Patented July 30, 1957

180,714

SAND MOLDERS' WORKBENCH

Peter S. Hardy, Trumbull, Conn., assignor to Peerless
Aluminum Foundry Co., Inc., Bridgeport, Conn., a
corporation of Connecticut

Application July 25, 1956, Serial No. 42,386

Term of patent 14 years

(Cl. D33—7)

Fig. 1.

Fig. 2.

Fig. 3.

Fig. 4.

Fig. 1 is a perspective view of the sand molders' workbench showing my new design, of which the top unit shown in full lines is the dominant feature, the dotted lines indicating the supporting stand;

Fig. 2 is a front elevation;

Fig. 3 is a side elevation; and

Fig. 4 is a top plan view.

The back of the top unit is of conventional configuration.

I claim:

The ornamental design for a sand molders' workbench, substantially as shown and described.
